Attest

UNITED STATES PATENT OFFICE.

CARL ARNOLD, OF NUERMBERG, GERMANY.

POCKET LAMP.

Application filed June 7, 1927, Serial No. 197,184, and in Germany January 31, 1927.

Mechanical pocket-lamps are known in which, by compressing of a segment-lever a gear wheel mechanism is operated so that by the same the cerium-stones are made to 5 rotate in sliding upon an emery-disk so that a permanent production of sparks is obtained. Pocket-lamps of this type present the inconvenience that they are very expensive and of limited illuminating effect, as 10 the repeated depressing of the segment-lever is rather fatiguing so that it is soon impossible to obtain the rapid rotation necessary for the production of strong sparks.

The inconveniences are avoided, according 15 to the invention which relates to a pocket-lamp of simple and cheap construction. According to the invention a toothed-wheel-mechanism on which cerium-stones, a reflecting plate and a ray-regulator are 20 mounted, is rapidly rotated by means of a spring-controlled rack, the bushels of sparks which are produced being rejected by the ray-regulator upon the paraboloidal reflecting wall of a casing so that the light 25 rays are projected through a lens.

An embodiment of the invention is shown, by way of example, in the accompanying drawing, in Fig. 1 in section and in Fig. 2 in top plan view.

30 In slots of the end walls of a casing α a rack b is guided which engages with a pinion f on a vertical shaft c said shaft being shiftably mounted in said casing. By a pressure exerted upon the outer end of rack b the vertical shaft c is shifted in being rotated at the same time so that a spur-wheel d , rigid with the pinion f comes into gear with a pinion g which is thus rapidly rotated together with the vertical shaft h on 40 which it is keyed. A spring i , fixed at the one end to the front wall of the casing and at the other end to the inner end of rack b serves for returning this rack, and through the same, the shiftable shaft c into the initial position. On the top plate of the casing α an emery-disk k is fixed and also a paraboloidal wall l at the top end of which, by means of a mounting m , a lens n is screwed.

50 The vertical shaft h carries on its portion,

which projects into the space enclosed by the paraboloidal wall l , a ray-regulator o which consists of a horizontal bar having sector-shaped end portions, said regulator o serving at the same time as fly-wheel. At 55 the middle of the regulator o flaps p are bent downward between which vibrating lever q are suspended which carry each a cerium-stone r at the outer end. A nut s screwed on the threaded top end of shaft h 60 serves to secure the regulator o , with the vibrating-levers q in their position.

The operation is as follows:—

By a pressure exerted upon the projecting end of rack b the shaft h carrying the 65 ray-regulator and the vibrating levers with the cerium-stones is rapidly rotated through the intermediary of the gear wheels f , d , g so that bushels of sparks are produced by the cerium-stones sliding on the emery-disk 70 k . These sparks strike onto the ray-regulator which projects the same onto the reflecting surface so that the light produced is projected through the lens. The ray-regulator serves at the same time as fly-wheel 75 so that the spark-production continues even during the return-movement of the rack.

I claim:—

1. A pocket-lamp comprising in combination with a casing, an emery disk mounted 80 on said casing, a vertical shaft journaled in said casing, means for rapidly rotating said vertical shaft, a paraboloidal casing having a reflecting inner surface, a lens in the top end of said casing, a ray-regulator 85 fixed on said vertical axle, and elastic levers suspended underneath said ray-regulator and having at the end a cerium-stone resting upon said emery-disk so that the sparks produced by the rapid movement of said cerium-stones are thrown by said ray-regulator onto said reflecting surface and the light-rays projected through said lens.

2. A pocket-lamp comprising in combination with a casing, an emery disk mounted 95 on said casing, a vertical shaft journaled in said casing, means for rapidly rotating said vertical shaft, a paraboloidal casing having a reflecting inner surface, a lens in the top end of said casing, a ray-regulator 100

fixed on said vertical axle and consisting of a horizontal flat-bar with sector-shaped ends and serving at the same time as fly-wheel, downwardly bent flaps at the middle of said bar, elastic arms suspended between said flaps, a cerium-stone at the end of each arm and resting upon said emery disk, so that

the sparks produced by the rapid movement of said cerium-stones are thrown by said ray-regulator onto said reflecting surface ¹⁰ and the light-rays projected through said lens.

In testimony whereof I affix my signature.
CARL ARNOLD.
